PREVENTING EVAPORATION FROM OIL
STORAGE TANKSDavid W. Jayne, Wilmington, Del., assignor to
E. I. du Pont de Nemours & Company, Wilming-
ton, Del., a corporation of Delaware

Application October 4, 1939, Serial No. 297,797

1 Claim. (Cl. 220—26)

This invention relates to tanks in which volatile liquids are stored and more particularly to active storage tanks containing gasoline or other volatile fractions.

In tanks of this kind the volume of the liquid is constantly changing due to additions and withdrawals of the contents. As the gasoline is withdrawn, fresh air enters the tank and becomes saturated with the vapors of the gasoline, and when the gasoline is added to the tank, the large volume of air saturated with the gasoline vapors escapes into the atmosphere and is lost. Where the volume of the gasoline in the tanks changes constantly by reason of additions and withdrawals, the amount of the vapors lost becomes enormous. Vapors of volatile liquids are also lost even when the content of the tank is not changed because of the expansion and contraction of the vapors above the liquid surface due to changes in temperature.

Many devices have been proposed to eliminate this loss. One method now in use to eliminate evaporation losses involves placing a pontoon roof within the tank. A pontoon roof is a self-contained element fitting within the shell of a storage tank and replacing the usual roof of a storage tank. Such a pontoon is adaptable to construction in new storage tanks but is not economical for existing tanks as the original roof of the tank must first be removed. Such pontoon roofs reduce the effective volume of the tank by the volume of the pontoon element.

Another disadvantage of the pontoon roof is that rain must be collected in a basin and allowed to overflow through a siphon drain into the liquid content below and settle to the bottom of the tank and must be removed from time to time.

It is, therefore, an object of this invention to provide means for preventing the evaporation of the volatile components of liquids which may be applied to either existing or new tanks. Another object of this invention is the provision of a device adapted to float on the surface of the liquid in a storage tank through which vapors cannot pass and is highly resistant to liquids which are likely to be stored in such tanks. A still further object is the provision of a floating device which may be installed in a storage tank by introducing the materials through the conventional manhole with which practically all such tanks are provided. Other objects will appear as the description of the invention proceeds.

These objects are accomplished by providing a layer of buoyant material which is covered by a membrane of fabric coated with a material which

is not penetrated by the vapor of the liquid contained in the tank and which will float on the surface of the liquid and is non-rigid.

The invention will be more clearly understood by reference to the drawings in which Figure 1 is a top plan view along the line 1—1 of Figure 3. In this figure parts are broken away to show the construction and arrangement of the parts.

Figure 2 is a detailed view of a vertical section along lines 2—2 of Figure 1.

Figure 3 is a diagrammatic section of a tank in which the product of the invention is installed.

Figure 4 is a plan view similar to Figure 3 except that the means for preventing the escape of vapors about the central support is different as will be explained hereinafter. In all the figures the same numerals refer to the same parts.

In Figure 1 the wall of the tank is indicated as 1. The buoyant material is shown as 2 and the membrane stretched over and secured to the buoyant material is represented as 3. In Figure 2 the detail of the method of preventing evaporation losses at the periphery of the buoyant material is shown. In this figure the membrane 3 extends over the end of the buoyant material 2 and forms a wiper which bears against the tank 1. An auxiliary wiper 4 is provided to further prevent losses. In Figure 2 this is illustrated as being inserted between two blocks 5 and 6 of buoyant material. The auxiliary wiper 4 may be attached to the bottom of the buoyant material 2 or a complete second membrane may be provided over the entire lower side of the buoyant material.

In Figure 3 the walls of the tank are represented as 1. The buoyant material and membrane are shown as 2 and 3, respectively. The roof is indicated as 7, while 8 is a vent to allow air to enter and escape from the tank as it is being emptied and filled. The central support for the roof is shown as 9, and as suggested above, instead of one central support there may be a plurality of such supports scattered throughout the tank. It is to be understood that a hole provided with wipers shown in Figure 2 occurs at each vertical support. A pipe 10 is provided for the passage of liquids into and out of the tank. At any convenient place a manhole illustrated as 11 may be provided in the tank.

The description of Figure 4 is the same as that of Figure 3 except that the means for preventing losses about the central or other support is different. In this figure a tubular piece of membrane 12 is attached to a collar 13 and also to the buoyant material 2. The length of this tube is such that when the tank is emptied completely and

the buoyant material 2 is close to the bottom of the tank, the tube will be just extended entirely in a vertical position.

In the operation of the device, oil or other volatile liquid is pumped in through the conduit or pipe 10. As the surface of the liquid rises the buoyant material floats on its surface and thereby prevents the evaporation of the liquid over the surface of the liquid where it is present. At the edges of the buoyant material the wipers 4 prevent the evaporation through the small passages between buoyant material and the walls or supports of the tank. As the liquid in the tank rises, the wipers take the position shown in the heavy lines in Figures 3 and 4. In Figure 4 the tubular member 12 will fold back upon itself as shown in solid lines in this figure. As the liquid is emptied through conduit 10 from the tank, the wipers take the position shown in the dotted lines in Figures 3 and 4, and the tubular member of Figure 4 will approach its fully extended position as the buoyant material reaches the bottom of the tank.

While I have described the invention as suitable for gasoline, it is to be understood that it is equally suitable for crude petroleum, naphtha, benzene, and practically all volatile organic liquids. It is likewise suitable for application to tanks wherein non-volatile liquids having volatile components are stored. It is also to be understood that any buoyant material sufficiently light to float upon a liquid and support an impermeable membrane is suitable in the invention. I prefer, however, to use cork or balsa wood blocks. These blocks may be impregnated or coated with resins, lacquers, or any material which is effective in preventing the absorption of the liquid with which it is in contact. The membrane may be any suitable impregnated fabric. I have found however, that a strong woven canvas impregnated with neoprene which is a rubber-like plastic polymer of 2 chloro 1,3, butadiene on one or both sides is particularly well adapted to the present invention due to its imperviousness to petroleum and similar liquids. This membrane may be prefabricated to the desired dimensions or introduced into the tank in segments and assembled within the tank. Any seams made within the tank and not previously rendered impervious may be made so by an appropriate cement such as neoprene cement.

One method of installing the device herein dis-

closed within the tank is to introduce cork blocks through the manhole 11 and place them close to each other over the entire area of the floor of the tank. The membrane is then placed over the cork blocks and fastened by any suitable means such as by staples to the blocks. It is advisable to seal the heads of the staples with a suitable cement.

It is to be understood that the figures are diagrammatic and not drawn to scale and that any of the parts may be enlarged or diminished without departing from the spirit of the invention. For example the blocks of buoyant material may be much larger than those shown in Figure 1 or for certain purposes they may be relatively small. In any event they should not be placed so close together or fastened so as to be rigid since many advantages flow from an arrangement wherein the blocks are placed in an articulated position; that is, where there is a slight space between the blocks, and they may move slightly with relation to each other. When so arranged the entire covering of the liquid rises and falls smoothly and evenly and does not bind when passing over rivets or other protuberances in the walls of the tank or other supports.

It is apparent that many widely different embodiments of this invention may be made without departing from the spirit and scope thereof, and therefore, it is not intended to be limited except as indicated in the appended claim.

I claim:

A floating roof for installation in a storage tank for the prevention of evaporation of liquids stored therein which comprises a large number of substantially contiguous articulated blocks of buoyant material and a continuous impervious membrane covering the upper surface of all of the said blocks and attached thereto and extending therebeyond continuously throughout the periphery of said roof and providing a flexible sealing wiper for contacting the tank wall, the said membrane being flat between the said blocks and lying in the same plane as the upper surfaces of said blocks, said device further having an auxiliary flexible wiper positioned beneath and in spaced relation to said first named wiper and co-operating therewith and with the tank wall.

DAVID W. JAYNE.
